UNITED STATES PATENT OFFICE.

JOSEPH W. MOORE, OF OBERLIN, LOUISIANA, ASSIGNOR OF ONE-HALF TO RIPLEY G. CORKERN, OF OBERLIN, LOUISIANA.

TYPEWRITER.

Application filed April 7, 1923. Serial No. 630,518.

To all whom it may concern:

Be it known that I, JOSEPH W. MOORE, a citizen of the United States, residing at Oberlin, in the parish of Allen and State of Louisiana, have invented certain new and useful Improvements in Typewriters, of which the following is a specification, reference being had to the accompanying drawings.

10 This invention relates to improvements in typewriters and more particularly to improvements in carriage return mechanism for typewriters.

15 An important object of the invention is to provide in combination with the typewriter a continuously running motor and means whereby the motor may be connected to the carriage to return the carriage upon completion of the line of typing.

20 A further object of the invention is to provide a device of this character in which connection of the motor is operated through a depressible key conveniently arranged and in which the motor is disconnected from the carriage automatically.

25 A further object of the invention is to provide an automatic means for disconnecting the carriage, serving as a positive stop to limit the movement of the carriage.

30 A further object of the invention is to provide means whereby the return movement of the carriage operates the platen of the carriage to shift the same.

35 A still further object of the invention is to provide a device of this character which may be readily applied to a typewriter and when so applied is so positioned and constructed as to in no manner interfere with the normal operation of the typewriter to which it is attached.

40 These and other objects I attain by the construction shown in the accompanying drawings, wherein for the purpose of illustration is shown a preferred embodiment of my invention and wherein:—

45 Figure 1 is a side elevation showing apparatus contructed in accordance with my invention, the typewriter being indicated in dotted lines.

50 Figure 2 is a plan view thereof, the typewriter being similarly indicated.

55 Figure 3 is an enlarged sectional view taken through the operating mechanism.

60 Figure 4 is a perspective view showing

the operating mechanism for the platen; and

Figure 5 is a perspective view showing the adjustable stop member and operating mechanism disconnecting device.

Referring now more particularly to the drawings, the numeral 10 indicates a typewriter frame, 11 the shiftable carriage thereof and 12 the platen roller of the carriage. In the typewriter with which the present invention is disclosed a pair of rearwardly extending arms 13 are provided upon the platen between the rear ends of which is disposed a notch bar 14 upon which are mounted adjustable stop members 15 employed for limiting the movement of the carriage to obtain a desired spacing of typing. This type of typewriter likewise has extending from the rear of the frame 10 thereof a pair of spaced lugs 16.

In accordance with my invention I mount 75 intermediate these lugs a rock shaft 17 having a depending arm 18 which is connected by a link 19 with one arm of a bell crank key lever 20, the opposite arm of which is provided with a depressible key 21 normally held in elevated position by a spring 22. To the frame 10 I secure supports 23 upon which is mounted a motor 24, the armature shaft 25 of which extends over the rack bar and is provided at its outer end 85 with a flange 26. This shaft has secured thereto one member of a cone clutch 27 facing and in spaced relation to the flange 25.

Likewise mounted upon the shaft 25 is a sleeve 28 provided at that end thereof next 90 adjacent the flange 26 with a gear wheel 29 engaging the teeth of the notch bar and at its opposite end with a second member 30 of the friction clutch. This sleeve is provided with an annular groove 31 receiving pins 32 upon the ends of arms 33 secured to the rock shaft 17 and extending upwardly therefrom.

It will be seen that by depression of the key 21 against the action of the spring 22, 100 the link 19 will be moved forwardly with the result that the arms 33 will be thrown rearwardly, moving the sleeve 28 rearwardly and bringing the clutch elements 27 and 30 into engagement, thus connecting the sleeve 105 with the motor shaft and causing the gear 29 to be rotated. By this rotation the carriage 11 will be shifted longitudinally to po-

sition for beginning a new line of typing, the finger being held upon the key during shifting of the carriage.

In order to provide for positive disconnection of the clutch sections 27 and 30 when the clutch has traveled a predetermined distance, I secure to the shaft 17 a fourth arm 34 having at its upper end a wedge-shaped extension 35 adapted for engagement with the adjustable stop member 36 and by such engagement to be shifted toward the rack bar. This shifting of the arm 34 toward the rack bar causes an oscillation of the rock shaft 17, with the result that the clutch sections are disengaged. This shifting further places the arm 34 so that it is directly in the path of the stop member 36 with the result that movement of the carriage is positively terminated at the time of disconnection of the clutch.

It is well known that shifting of the carriage is usually accomplished by means of a shifting lever 37 which is pivoted and which when engaged with the hand, shifts prior to any shifting movement of the carriage. This shifting movement is in all typewriters with which I am familiar employed to shift the platen roller 12. In the present instance I have disclosed the lever 37 as a bell crank lever having one arm adapted for engagement with the hand, as at 38, and the other arm provided with a dog 39 coacting with the ratchet 40 carried by the end of the platen roller 12. It will be obvious that when the carriage is shifted by the mechanism hereinbefore described this lever will not be operated since it is engaged by the hand and I accordingly pivot upon the carriage 11 at the opposite end thereof from the lever 37 a lever 41, one end of which is connected with the operating end of the lever 37 by a link 42 extending longitudinally of the carriage. The opposite end of this lever is bent into proximity to a stationary part of the typewriter frame 10 and upon this part of the typewriter frame and in such position as to be engaged by the lever 41 I place a stop member 43, the lever engaging this stop member is rotated upon its pivot with the result that the lever 37 is shifted as if by engagement with the hand and the platen roller accordingly rotated. From the foregoing it will be obvious that by use of mechanism constructed in accord-

ance with my invention in combination with the typewriter, the carriage may be shifted without the necessity of elevating the hand from the keys and the operating mechanism will be automatically disconnected at the proper time and the platen roller shifted. It will furthermore be obvious that this structure as hereinbefore set forth is capable of some change and modification without materially departing from the spirit of my invention and I accordingly do not limit myself to such specific structure except as hereinafter claimed.

I claim:-

1. In combination with a typewriter having a shiftable carriage embodying a notch bar, a motor rigidly secured to the typewriter frame and having a shaft extending over the notch bar, a sleeve rotatably mounted upon the shaft and provided upon one end with a gear engaging the teeth of the notch bar upon the opposite end thereof with one element of the friction clutch, a second element of the friction clutch secured to said shaft, said sleeve having a groove therein, shiftable arms having pins thereon engaged in the groove at diametrically opposed points and key operated means for shifting said arms to move said sleeve in a direction bringing the clutch elements into engagement. 85

2. In combination with a typewriter having a shiftable carriage embodying a notch bar, a motor rigidly secured to the typewriter frame and having a shaft extending over the notch bar, a sleeve rotatably mounted upon the shaft and provided upon one end with a gear engaging the teeth of the notch bar upon the opposite end thereof with one element of the friction clutch, a second element of the friction clutch secured to said shaft, said sleeve having a groove therein, shiftable arms having pins thereon engaged in the groove at diametrically opposed points, key operated means for shifting said arms to move said sleeve in a direction bringing the clutch elements into engagement, and automatic means for shifting the arms in an opposite direction when the carriage has traveled a predetermined distance. 90

In testimony whereof I hereunto affix my signature.

JOSEPH W. MOORE.
